US00D556253S

(12) **United States Design Patent** (10) **Patent No.:** **US D556,253 S**
(45) **Date of Patent:** **** Nov. 27, 2007**

(54) **PRINTER**

(75) Inventors: **Yun-Gi Hong**, Seoul (KR); **Seok-Won Bae**, Seoul (KR); **Jun-Won Bae**, Seoul (KR); **Bong-Uk Lim**, Seoul (KR)

(73) Assignee: **Samsung Electronics Co., Ltd.**, Kyunggi-do (KR)

(**) Term: **14 Years**

(21) Appl. No.: **29/261,037**

(22) Filed: **Jun. 6, 2006**

(51) **LOC (8) Cl.** **18-02**

(52) **U.S. Cl.** **D18/50**

(58) **Field of Classification Search** **D18/4.5, D18/14, 19, 36-39, 50, 53, 54-54.1, 55; D14/420-425, 462-470; 400/613, 613.1-613.4, 400/690.1-690.4, 691-694**

See application file for complete search history.
